UNITED STATES PATENT OFFICE.

WENDELL E. HERBST, OF HARTFORD, CONNECTICUT.

DESIGN FOR A SLED.

SPECIFICATION forming part of Design No. 25,550, dated May 26, 1896.

Application filed March 10, 1896. Serial No. 582,659. Term of patent 14 years.

To all whom it may concern:

Be it known that I, WENDELL E. HERBST, a citizen of the United States, residing at Hartford, in the county of Hartford and State of Connecticut, have invented a certain new and original Design for Coasting-Sleds, of which the following is a specification.

Referring to the accompanying drawings, wherein the design for a sled is illustrated, Figure 1 is a plan, Fig. 2 is a side elevation, and Fig. 3 is a view of the rear end, of the sled embodying the design.

The pair of runners 1, which are approximately square in cross-section and are parallel with each other, extend straight for most of their length and then curve upward somewhat at their front ends.

The seat-supports, four in number, all extend from the runners upward to the seat, inclining toward each other—that is, the two front supports are inclined toward each other and toward the rear supports, and the rear supports 3 incline toward each other and also toward the front supports. These supports are of such length that the seat is held high enough to permit the coaster to sit upright when sliding downhill, and the braces 4 extend across between the two front inclining supports and between the two rear inclining

supports in such manner as to give the appearance of the letter **A** to the runners, supports, seat, and braces when looking from the front or looking from the back, as shown in Fig. 3, while the braces 5 extend across between each of the two front inclining supports and the two rear inclining supports, so as to produce the appearance of a broad **A** when looking at the sled from either side, as shown in Fig. 2. The tops of the letters are formed by the seat 6, which, when seen in plan, is an oblong piece with rounded ends and a narrow center, as illustrated in Fig. 1.

The leading feature of the design resides in the location, inclination, and proportional length of the supports and braces, whereby the features described and shown are produced, the resultant effect of which is the sled with a high seat and a frame which indicates the letter and plain substantial artistic strength.

I claim as my invention—

The design for a sled herein shown and described.

WENDELL E. HERBST.
